UNITED STATES PATENT OFFICE.

WILBERFORCE BEECHER HAMMOND, OF BROOKLINE, MASSACHUSETTS.

SPRINKLER ATTACHMENT.

1,077,830.

Specification of Letters Patent.

Patented Nov. 4, 1913.

Application filed March 21, 1913. Serial No. 755,823.

To all whom it may concern:

Be it known that I, WILBERFORCE BEECHER HAMMOND, a citizen of the United States, and resident of Brookline, in the county of 5 Norfolk and State of Massachusetts, have invented new and useful Improvements in Sprinkler Attachments, of which the following is a specification.

My invention relates to the construction 10 of sprinkler systems for fire protection, and consists in certain improvements by which sprinkler heads of the ordinary standard type may be safely applied to water circulation pipes which, for purposes of heating, 15 may carry water at a much higher temperature than that which will suffice to release the automatic sprinkler head. In some respects the inventions herein shown are improvements upon an invention shown and 20 described in an application for United States Patent, Serial No. 664,435, filed by me December 7, 1911.

The purpose of the present improvements is to provide a sure means for entrapping 25 gases in an offset to which a sprinkler head is attached in such manner that the sprinkler head and a large portion of the offset is occupied by such gases. These therefore exclude water from a relatively large portion 30 of the offset, retard or prevent local circulation, due to thermal influences, of such water and therefore enable the metal of which the offset is preferably composed to disperse heat communicated by conduction 35 from the main pipe in which hot water will circulate, to an extent sufficient to maintain the sprinkler head under normal conditions at a temperature safely below that at which it is intended to operate as an automatic 40 sprinkler.

In the drawings hereto annexed, which illustrate sundry forms of my invention,—Figure 1 is a side elevation, partly in section, of a sprinkler offset with a sprinkler 45 thereon; Fig. 2 is a similar view of another form; Fig. 3 is a cross section at the line 3—3 of Fig. 2; Fig. 4 is an elevation, partly in section, of another form; Fig. 5 is an elevation, partly in section, of another form; 50 and Fig. 6 is an elevation, partly in section, of still another form.

In all the forms of sprinkler offset herein illustrated, the characteristic feature of my invention will be found, namely, a partition 55 within the sprinkler offset which serves as

a dam to prevent water, which may enter from the main pipe, from coming in contact with a considerable portion of the metal of which the offset itself is composed. This partition may operate as an inverted dam as 60 in Figs. 1, 2 and 4, which allows water to flow in under it but prevents water from rising above the lip of the dam, or as a dam such as shown in Figs. 4 and 6, in which water is normally prevented from flowing 65 over the lip of the dam into contact with the walls of the sprinkler offset.

Referring to Fig. 1, M represents a main pipe through which water at high temperature may be circulated. A quarter turn 70 union A is secured to a nipple or to a T coupling on the main pipe M and a length of pipe P is secured in the quarter turn A and carries at its other end a quarter turn C to which the sprinkler head S is secured in the 75 usual manner. The pipe P has formed or secured within it a transverse partition B which operates as an inverted dam which prevents water under normal conditions from rising above the level indicated by the 80 dotted line L. Although the water may rise to this level under some conditions of pressure within the system, it will not rise above that level to any material extent; and although the water may lie in contact with 85 the lower portion of the pipe P, the presence of the partition B will prevent circulation of water except possibly in that portion of the offset which lies between the said partition and the main pipe M. Thus, the 90 greater portion of the offset is occupied by dead water in its lower part and by gases in its upper part, both of which are very poor conductors of heat, and the metal of which the offset is composed will readily radiate 95 heat conducted to it so rapidly as to maintain the sprinkler head S at a safe temperature, considerably below the temperature at which standard sprinkler heads are set to release. 100

Another form of my invention is shown in Figs. 2 and 3, and this I am inclined to regard as a preferable form. Here the partition marked B' consists of a tapered tube of thin metal such as tin, which is made to fit water-tight within the pipe P at that end of the tube B' which lies nearest the main pipe M. The tube B' in this form lies in contact with the lower side of the pipe P so that its open end B² is in the position shown 110

in Figs. 2 and 3. Here the lip formed by the upper part of the orifice B^2 constitutes an inverted dam which like the transverse partition B in Fig. 1, prevents water from rising materially above the level of the dotted line marked L . The tubular form of partition may be employed as a dam in that form of my invention illustrated in Fig. 4, in which the offset pipe P' extends vertically upward from the main pipe M . The tube B' is secured or sealed at its lower end to the pipe P' and extends upward so that its opening B^2 is well above the level to which, under any probable condition, water will rise. If water stands at the level marked L^2 in this tube, although it may so circulate as to be very nearly as hot as the water in pipe M , the fact that the tube B' is so proportioned as to leave a space all around it between it and the wall of the tube P' insures the presence of entrapped gases in contact with substantially the entire length of the pipe P' , and these gases being poor conductors of heat, will enable the pipe P' , even though it be quite short, say three or four inches, to take care of communicated heat by radiation and keep the temperature of the sprinkler head S at a safe degree. If it should so happen that some water flows over the opening B^2 of the pipe B' , it will lie in the contracted annular space between the top B' and the pipe P' and will there constitute simply a film of dead water too thin to set up an appreciable amount of circulation, so that presence of such water will not materially impair the heat-insulating capacity of the offset taken as a whole.

In Fig. 5 there is illustrated another form in which the offset pipe P^2 , joined at one end to a union A' and at the other to union C , extends downward at an angle. The tapered tube B' inside of the offset pipe P^2 here performs its function as an inverted dam in substantially the same way as in the form shown in Fig. 2. The form shown in Fig. 5, however, is not particularly recommended if only for the reason that it is a form which does not provide for drainage back into the main pipe M . Fig. 6 shows a form intermediate between those of Figs. 2 and 4 in which a pipe P^3 , joined to unions A^2 and C^2 , extends upward at an angle and contains the partition pipe B' centrally disposed in the pipe P^3 so as to leave a space all around the tube B' . The operation of the offset so constructed will be

substantially the same as that of the form shown in Fig. 4.

In all cases the principle of operation is characterized by the function of the partition which, whatever its form, serves to prevent any body of water voluminous enough to set up internal circulation from coming into contact with a considerable portion of the metal of which the offset is composed so that the heat coming from the main pipe M and the water therein as a source, is controlled and taken care of by radiation so as to keep the temperature of the sprinkler head S at a safe limit.

What I claim and desire to secure by Letters Patent is:—

1. In a sprinkler attachment, the combination of an offset adapted to be secured to a main water pipe, a sprinkler head at the end of said offset, and a partition in said offset with its lip at such level therein as to maintain a considerable portion of the offset free from contact with water.

2. In a sprinkler attachment, the combination of an offset, adapted to be secured to a main water pipe, a sprinkler head at the end of the offset, and a tube inside the offset, sealed to the walls of the offset at the end of the tube nearer the main pipe, and of such dimensions as to leave a space between the tube and the inner wall of the offset.

3. In a sprinkler attachment, an offset comprising a horizontal tubular member adapted to be secured to a main water pipe, a sprinkler head at the end of the offset, and a partition in said horizontal tubular member, having its lip at such level as to maintain a considerable portion of the offset free from contact with water.

4. In a sprinkler attachment, the combination of an offset adapted to be secured to a main water pipe and comprising a horizontal tubular member, a sprinkler head at the end of the offset, and a tube inside the offset, sealed to the walls of the offset at the end of the tube nearer the main pipe, and of such dimensions as to leave a space between the tube and the inner wall of the horizontal member of the offset.

Signed by me at Boston, Massachusetts, this 18th day of March, 1913.

WILBERFORCE BEECHER HAMMOND.
